UNITED STATES PATENT OFFICE.

LOUIE GLENN WILSON, OF MORNING SUN, IOWA.

AUTOMONOCYCLE.

1,345,727.

Specification of Letters Patent.

Patented July 6, 1920.

Application filed May 3, 1919. Serial No. 294,523.

To all whom it may concern:

Be it known that I, LOUIE GLENN WILSON, a citizen of the United States, residing at Morning Sun, county of Louisa, State of Iowa, have invented a certain new and useful Improvement in Automonocycles, and declare the following to be a full, clear, and exact description of the same, such as will enable others skilled in the art to which it pertains to make and use the same, reference being had to the accompanying drawings, which form a part of this specification.

My invention relates to automonocycles, and means for propelling, steering and balancing the same.

The object is to provide an automonocycle with adapted mechanical means for the utilization of the gyroscope reaction of a conventional form of gyroscope in the maintenance of stability.

Another object is to provide an automonocycle substantially as above with an air propeller in which it is possible to change the incidence of the blades of said propeller so as to regulate the forward movement of said vehicle or reverse the same, without interfering with the constant running of the motor which drives such propeller.

Another object is to provide an automonocycle substantially as above with means of utilizing gyroscopic reaction produced by a disturbance of the plane of rotation of a rotative wheel embodied in said gyroscope to guide the vehicle.

In the drawings:

Figure 1 is a side elevation of my improved automonocycle.

Fig. 2 is a plan view partly cut away.

Fig. 3 is an elevation of the rotative wheel carrying the air propeller blades.

Fig. 4 is a detail view in fragmentary section of the rack and pinion device for changing the incidence of the propeller blades, taken on line 4-4 of Fig. 3.

Fig. 5 is a perspective of the handle.

Fig. 6 is a sectional view of the handle.

Fig. 7 is a view of the rack and pinion operating means.

Numeral 1 designates the single wheel of the automonocycle. 2 is the axle on which said wheel rotates. 3 is a forked member, carried one on each extremity of axle 2, and which pivotally supports upwardly diverging rods 4. These rods are four in number, two on each side of the wheel.

Rods 4 are fitted in cylinder members 5, which are pivotally attached to the under surface of a gyroscope casing 6 as at 7.

Cylinder members 5 are provided with compression springs 8, against which rods 4 act as pistons.

The gyroscope casing supports in any suitable manner a seat 9, which is provided with a foot-rest 10.

11 is the supporting rack, composed of two halves, one being provided on each side of wheel 1, and adapted to be let down to support the cycle when the same is to be parked.

12 is a mud guard.

13 is a fuel tank carried in the rear of the seat.

14 is the engine assembly. This is a conventional compression gas engine, and there is no claim of novelty to it. 15 and 15^a designate two opposed air cooled cylinders. These cylinders are provided with fins to increase the surface of radiation. 16 is a generator. 17 is the crankshaft. 18 is a rotative wheel serving not only as a propeller but also as a fly wheel. The engine is complete for its type and the details are conventional.

The engine assembly 14 is mounted upon shaft 19, which shaft 19 is pivotally mounted between two rearwardly projecting arms 20 and 20^a of the frame.

To one extremity of the shaft 19 is attached a short arm 21 adapted for the application of rotary force to shaft 19.

The engine is normally balanced on said shaft 19 as it is pivotally mounted between the rearwardly projecting arms of the frame 20 and 20^a.

On the crank shaft 17 is mounted a rotative wheel 18, provided with spokes 22, propeller blades 23—three in number being here shown—but in such number as is thought desirable. Such propeller blades 23 are mounted on a longitudinal axis 24. The inner extremities of blades 23 carry a pinion 25, which operates in connection with a rack 26 for the changing of the incidence of the blades.

It will be seen that reciprocal movement of such rack over the pinion may be made to produce the desired angle of incidence in the blades, as shown in Fig. 4.

The inner ends of rack arms 26 are fastened to a disk 27, which is fitted with a grooved collar 28. Collar 28 receives and

is in engagement with a forked member 29, which forked member is provided with inwardly projecting lugs 30, adapted for engagement in the groove of the collar.

5 Said disk with collar attached and carrying rack arms 26 is adapted for a longitudinal movement on shaft 17 by means of a rocker arm 31, which is pivotally mounted at 32 to the rearward end of one of the cylinders. Said rocker arm 31 is operated by means of a chain composed of link 33, rocker arm 34 and link 35 connected with the operating handle at 36.

Handle assembly 37 is composed of two 15 main handle portions 38 and 39. The handle 37 is pivotally mounted on the frame at 40.

The upper portion of said handle member 39 is normally held in engagement with the 20 lower portion 38 by means of the enmeshed teeth at 41 and the handle is operated as a whole backward and forward upon its pivotal point 40 (Fig. 6).

Said upper portion 39, however, is, as 25 shown, adapted to be disengaged by merely lifting up and disengaging the mesh, when the upper portion 39 may be reciprocated upon its vertical axis. This would reciprocate downwardly projecting rod 42, which is 30 permanently inset in said handle portion 39, oscillating the horizontal projecting arm 36, transmitting the movement to link 35 which is pivotally connected at 36. Thus through the rack and pinion the incidence 35 of the blades 23 may be changed.

A parallel chain is provided consisting of a jointed link 43 pivotally mounted to short arm 21, which serves to apply a tilting force to the engine assembly through the shaft 19. 40 The forward end of link 43 is pivotally mounted to the lower extremity of handle 37. This chain is brought into action when the handle is used as an entirety upon its pivotal point 40, the other chain in such use remaining idle. Thus each chain is adapted for 45 movement independent of the other.

With the propeller blades set at that angle which will give the greatest thrust forward, the speed of the cycle may be regulated without interfering with the speed of the motor, 50 by merely changing the set angle of the blades from the above position to one of zero or approaching the zero position of forward thrust. The blades might even be moved to 55 that position where the pull would be backward instead of forward.

It will thus be possible to deviate from the direct line of travel while the motor is running at a high speed by merely changing the 60 incidence of the blades and then operating the steering mechanism, *i. e.* it would be possible to decrease the speed of the vehicle by such action to permit such deviation without decreasing the speed of the motor.

65 Gyroscope casing 6 incloses a gyroscope

suitably mounted on a vertical axis, the propulsive means a motor likewise contained within the casing. There is nothing novel in the form of gyroscope or its mounting or means for rotating the same. This gyroscope is preferentially mounted in an air tight casing so as to revolve *in vacuo*. It is a simple form of gyroscope with no automatic means for hurrying the precession. The precession however, may be accelerated 75 and the machine maintained in its upright position by the movement of the body of the rider.

Steering of the vehicle is secured by utilization of the principles of gyroscopic reaction. The rotative wheel 18 together with the engine assembly 14, pivotally mounted as shown on axis 19, comprises a form of gyrostatis. By means of hand lever 37, a tilting force is brought to bear, through short arm 80 21, upon shaft 19, tending to disturb the plane of rotation of rotative wheel 18. As a matter of fact practically no tilting occurs, but the gyrostatic reaction which results serves to turn the vehicle on its single wheel 85 in the desired direction, depending upon whether the impetus of tilting is upward or downward. With the rotative wheel revolving in a positive direction, *i. e.* counter-clockwise, as viewed from the seat of the cycle, 90 and the application of an upward tilting force through axis 19, there will be a resulting reaction resisting the disturbance of the plane of rotation of wheel 18, which will cause a rotation about the vertical axis indicated by the point of contact of the single wheel with the earth in a positive direction or to the left. The machine could be guided to the right if the tendency to tilt were downward. The reverse of this would be 95 true if the rotative wheel were rotating in a reverse or negative direction.

Having thus described my invention what I claim is:

1. In an automonocycle, in combination with an air propeller for driving the same, means for disturbing the plane of rotation of said propeller to accomplish the guiding of said cycle.

2. In an automonocycle, in combination with an air propeller rotating in a vertical plane, means for applying force tending to move said plane of rotation from the vertical to one at an angle thereto to accomplish the guiding of the cycle.

3. In an automonocycle, in combination with an air propeller rotating in a vertical plane, means for applying force tending to disturb said plane of rotation to guide the cycle.

4. In an automonocycle, in combination with an air propeller rotating in a vertical plane at right angles to the direction of travel of the cycle, means for applying force tending to move said plane of rotation 125 130

from the vertical to one at an angle thereto to guide the cycle.

5. In an automonocycle, a pusher air propeller rotating in a vertical plane on an axis parallel to the direction of travel, and means for applying force tending to disturb said plane of rotation of said propeller from the vertical.

10. In an automonocycle, an internal combustion engine, a driving shaft, an air propeller mounted on said shaft to rotate in a vertical plane, said engine shaft and propeller balanced on a horizontal pivotal axis extending at right angles to the direction 15 of travel, means for applying force tending to rotate said engine, shaft and propeller about said horizontal axis tending to move said air propeller from the vertical plane in which it is rotating to guide the cycle.

20. 7. In an automonocycle, an internal combustion engine, a driving shaft, an air propeller mounted on said driving shaft, said engine, shaft and propeller balanced and mounted on a rotatable shaft pivotally mounted at right angles to the direction of travel and means for disturbing the plane of rotation of said air propeller through rotative force applied to said rotatable shaft.

25. 8. In an automonocycle, in combination with a balancing gyroscope, an internal combustion engine, a driving shaft, and a rotative wheel on the rearward end of said driving shaft, said rotative wheel consisting of a rim, hub and a plurality of air propeller blades, said wheel, shaft and engine assembly mounted and balanced for rotation about a horizontal shaft pivoted to the frame of said cycle, means for applying a force tending to rotate said horizontal shaft 40 to produce a disturbance of the plane of rotation of said rotative wheel.

30. 9. In an automonocycle, the combination of an internal combustion engine, a driving shaft parallel to the direction of travel and an air propeller mounted on the rearward end of said driving shaft, said air propeller, driving shaft and engine assembly balanced and mounted on a horizontal axis pivotally mounted at a right angle to the direction 45 of travel of the cycle, and means for applying a force tending to rotate said engine assembly and air propeller about said horizontal axis.

35. 10. In an automonocycle, the combination of an internal combustion engine, a driving shaft, an air propeller mounted on said shaft, a horizontal shaft pivotally mounted at a right angle to the direction of travel of said cycle, on which shaft are mounted

and balanced said air propeller, driving 60 shaft and engine assembly, a short arm fixed to one end of said horizontal shaft, and means for steering the vehicle by oscillating said short arm tending to disturb the plane of rotation of said air propeller.

65

11. In an automonocycle, the combination of an internal combustion engine, a driving shaft parallel to the direction of travel of said cycle, an air propeller on said driving shaft, a rotative shaft horizontally disposed 70 at a right angle to said driving shaft on which said engine assembly driving shaft and air propeller are balanced and mounted, and means for applying revolving motion to said horizontally disposed rotatable shaft.

75

12. In an automonocycle, an internal combustion engine mounted on a rotative shaft disposed at a right angle to the direction of travel of said vehicle, an air propeller mounted on the driving shaft of said engine, 80 said engine assembly and air propeller balanced on said rotative shaft so that said propeller will rotate in a vertical plane, a short arm at one extremity of said rotative shaft, a lever pivoted by the driver's seat, 85 and linkage connecting said lever and short arm for the application of force to rotate said shaft.

13. In an automonocycle, a gyroscope rotating in a horizontal plane so disposed in a 90 casing located with relation to the seat of the rider that the directed swing of the body of the rider will accelerate the precession of the same, a driving shaft, an air propeller mounted on the rearward extremity 95 of said driving shaft, said engine assembly and air propeller balanced and mounted so as to have a horizontal axis on which it is pivoted for rotation, and means for applying rotative force tending to disturb the 100 plane of rotation of said air propeller.

14. In an automonocycle, a gyroscope rotating in a horizontal plane adapted for acceleration of its precession by the directed swaying of the body of the rider, an internal 105 combustion engine, a driving shaft, an air propeller mounted on said driving shaft to rotate in a vertical plane, said engine assembly, driving shaft and air propeller balanced and carried on a horizontal pivotally 110 mounted shaft, a short arm on one extremity of said pivoted shaft, means for applying force to said short arm to rotate said shaft tending to disturb the plane of rotation of said air propeller from that of the vertical.

115

In testimony whereof, I sign this specification.

LOUIE GLENN WILSON.
